UNITED STATES PATENT OFFICE.

JOSEPH SLEPIAN, OF SWISSVALE, PENNSYLVANIA, ASSIGNOR TO WESTINGHOUSE ELECTRIC & MANUFACTURING COMPANY, A CORPORATION OF PENNSYLVANIA.

PROTECTIVE DEVICE.

Application filed February 16, 1922. Serial No. 536,910.

To all whom it may concern:

Be it known that I, JOSEPH SLEPIAN, a citizen of the United States, and a resident of Swissvale, in the county of Allegheny and State of Pennsylvania, have invented a new and useful Improvement in Protective Devices, of which the following is a specification.

This invention relates to protective devices, more especially to lightning arresters, such as are described in my copending application, Serial No. 535,810, filed Feb. 11, 1922, for lightning arresters.

In the aforesaid application, I have described a new type of lightning arrester comprising, primarily, a series of plane plates or disks stacked in contact with each other, the said disks being composed of a material having a high specific resistance. In operation, the pile of disks is connected between a circuit to be protected and the ground so that, upon the circuit being subjected to abnormal voltage, sparking occurs between the plates causing a glow discharge to be established therebetween and allows the excess energy to flow to ground. Upon the return of the circuit voltage to a value but slightly below the breakdown voltage, the glow discharge ceases and substantially no current passes to the ground.

After a discharge, it has been found that in many cases an appreciable power current flows for a considerable length of time. This is due to several causes, chief among which are the large area of contact between the disks, and the loose particles of material that are formed upon frequent discharge through the arrester.

In view of this, one of the objects of the present invention is to provide a plate or disk structure for my new lightning arrester which shall be effective to reduce the power loss after discharge to a minimum.

It is a further object of this invention to provide a simple disk structure which may be manufactured at a low cost and which shall be adapted to quantity production.

In practising my invention, I provide a disk structure embodying a narrow, elevated portion or rib therein. Preferably, the rib is of material having a high specific resistance, generally considerably higher than that of the disk itself. I stack a series of such disks so that the rib on one face of one

disk contacts with the smooth or plane face of the next adjacent disk. This provides a simple structure which has a very high resistance to power current at a voltage below the discharge voltage of the arrester and still allows a ready path for a considerable volume of current above the discharge potential.

In the accompanying drawings, forming a part hereof, and in which like reference characters designate like parts;

Fig. 1 is a plan view of a disk made in accordance with this invention;

Fig. 2 is a side view of a pile of disks, and

Fig. 3 is a cross sectional view on an enlarged scale of one of my disks.

The disks 1 are formed of any suitable resistance material, preferably, but not necessarily, of material having a high specific resistance. I generally utilize a material consisting of kaolin, carborundum and graphite, which are mixed in a slightly plastic state, molded in suitable molds to the form shown and then baked to dry the material and form the same into a solid, coherent, wear-resisting body. One surface of each plate is provided with a rib or ribs 2, preferably formed integrally with the plate either in the molding process or by sandblasting the depressed portions between the ribs.

I then provide a heated plate which is generally in annular form or sometimes of ring form with a flat face. The plate or ring is heated to a high temperature, generally a cherry red heat, and a disk 1 is placed so that the rib 2 is in contact with the heated ring. The time of contact is determined so that the heating burns or oxidizes the carbon in the rib 2 only, raising the resistance thereof to the desired degree without affecting the resistance of the body of the disk at all. Generally, the heating is continued until the resistance of a disk 3 inches in diameter, $\frac{1}{8}$ inch thick, and having a rib or projecting portion about 3 mils high, is so great that it will pass less than one milli-ampere of current at 300 volts.

Generally, the specific resistance of the body portion of the disks is about 50 ohms per centimeter cube, and may be varied between wide limits, say between 25 and 100 ohms. The height of the ribs may vary

within wide limits, being as low as 1 mil, and I have used disks having ribs as high as 16 mils with success.

When the disks are stacked, as shown in Fig. 2, with the rib on one side of one disk, in contact with the smooth surface of the adjacent disk, a series of spaces 3 are formed between the disks. Upon a discharge being passed through the same, the glow discharge begins at the contact of the high resistance rib with the adjacent disk, the glow discharge then spreading over the entire plate, whereby a large current is discharged. When the voltage across the arrester is decreased below the discharge potential, the current passing through the arrester becomes very small and the amount of power lost thereby is practically negligible.

A disk of this type has many advantages over the plane disk which I have hitherto used. There are a few points of contact between the disks which form starting points for the sparkover and which allow the glow discharge to spread rapidly over the entire surface of the disk. The resistance of the contact points is very high, resulting in an extremely low leakage of current and a negligible power loss. The ribs are strong and do not crumble, even though they are subjected to rough handling.

Although I have described a specific embodiment of my invention, it is apparent that I may provide many modifications and variations in procedure and structure within the scope of this invention. For instance, I may modify the size and shape of the disks, the height and number of the ribs or projecting portions and the type of heating plate or ring. Although I utilize a material which has a high specific resistance for the entire body of the disk, it is apparent that only the rib portion need have a high specific resistance and that the body portion may be of relatively low resistance materials. The rib, although preferably formed integral with and initially of the same material as the body portion, may be formed separately or of different materials and may be united with the body in any suitable manner. These and other changes may be made in my invention without departing from the spirit and scope thereof.

I claim as my invention:

1. In a protective device, a substantially plane plate and an elevated portion thereon, the height thereof being between 1 and 16 mils.
2. In a protective device, a substantially plane plate and an elevated portion thereon, the height thereof being about 3 mils.
3. In a protective device, a substantially plane plate and an elevated portion thereon, said elevated portion having a higher specific resistance than the body of said plate.
4. In a protective device, a substantially

plane plate and a narrow, slightly elevated portion thereon, said elevated portion having a higher specific resistance than the body of said plate.

5. In a protective device, a substantially plane disk and a circular, elevated portion thereon, said elevated portion having a higher specific resistance than the body of said plate.

6. In a protective device, a plurality of plates and conducting spacer members therebetween.

7. In a protective device, a plurality of plates and conducting spacer members having a high specific resistance therebetween.

8. In a protective device, a plurality of plates and conducting spacer members having a high specific resistance therebetween and contacting with said plates over a relatively small portion of the area thereof.

9. A method of making plates which comprises forming a plate having an elevated portion thereon and then subjecting said elevated portion to a relatively high temperature.

10. A method of making plates which comprises forming a plate having an elevated portion thereon, placing said plate so that said elevated portion contacts with a heated member and maintaining said contact until the specific resistance of said elevated portion is raised.

11. A method of making plates which comprises forming a plate having an elevated portion thereon, placing said plate so that said elevated portion contacts with a heated member and maintaining said contact until the specific resistance of said elevated portion is raised until 300 volts applied to a metal plate in contact with the disc will pass less than 5 milli-amperes.

12. A method of making plates which comprises forming a plate having an elevated portion thereon and then increasing the resistance of said elevated portion.

13. A plate of high-resistance material comprising a substantially flat body portion and a plurality of rib portions thereon, the resistance of said rib portions being higher than that of the body portion.

14. An excess-voltage discharge device comprising at least one pair of juxtaposed plates, and a high-resistance spacing means on one of the plates interposed between said plates, the resistivity and spacing being such that the discharge device permits a relatively large current-flow at voltages above a predetermined value and prevents any substantial current-flow at voltages below said value.

15. A protective device comprising at least one pair of juxtaposed high-resistance plates having a discharge gap therebetween, and high-resistance spacing means interposed between said plates and united to one

- of the same, the specific resistance of said spacing means being higher than the specific resistance of said plates.
16. An excess-voltage discharge device comprising at least one pair of juxtaposed high-resistance plates having a discharge gap therebetween, at least one of said plates having an integral rib contacting with the other plate.
17. An excess-voltage discharge device comprising at least one pair of juxtaposed high-resistance plates having a discharge gap therebetween, at least one of said plates having an integral rib of increased specific resistance contacting with the other plate.
18. A space-current discharge device comprising at least one pair of electrode plates having a discharge gap therebetween, one of said plates carrying a rib contacting with the other plate for spacing the same.
19. A space-current discharge device comprising at least one pair of electrode plates having a discharge gap therebetween, one of said plates carrying a rib contacting with the other plate for spacing the same, the contacting surface of said rib being of higher specific resistance than the body portion of the plate which carries it.
20. A space-current discharge device comprising electrode plates having a discharge gap therebetween, the material of at least one of said plates having such resistivity as to cause the discharges in said gap to spread out, said plate carrying a rib contacting with the other plate for spacing the same.
21. A space-current discharge device comprising electrode plates having a discharge gap therebetween, the material of at least one of said plates having such resistivity as to cause the discharges in said gap to spread out, said plate carrying a rib contacting with the other plate for spacing the same, the contacting surface of said rib being of higher specific resistance than the body portion of the plate.
22. An excess-voltage discharge device comprising at least one pair of juxtaposed plates, and a high-resistance spacing means interposed between said plates and united to one of the same, the spacing being such that the space-current flow between the plates always takes the form of a glow discharge.
23. An excess-voltage protective device comprising at least one pair of juxtaposed high-resistance plates having a discharge gap therebetween, and a high-resistance spacing means interposed between said plates and united to one of the same, the resistivity and spacing being such that the protective device permits a relatively large current-flow at voltages above a predetermined value and prevents any substantial current-flow at voltages below said value.
24. A protective device comprising stacked electrode plates having at least one
- discharge gap therebetween, at least one of said plates being a substantially plane plate having a portion elevated between 1 and 16 mils.
25. A protective device comprising stacked electrode plates having at least one discharge gap therebetween, at least one of said plates being a substantially plane plate having an elevated portion of about 3 mils height.
26. A protective device comprising stacked electrode plates having at least one discharge gap therebetween, at least one of said plates being a substantially plane plate of high-resistance material having a portion elevated between 1 and 16 mils.
27. A protective device comprising stacked electrode plates having at least one discharge gap therebetween, at least one of said plates being a substantially plane plate of high-resistance material having an elevated portion of about 3 mils height.
28. A space-current discharge device comprising at least one pair of electrode plates having a discharge gap therebetween, one of said plates carrying a rib contacting with the other plate for spacing the same, the organization being such as to cause a glow discharge at voltages above a predetermined value and to permit no space-current discharge at voltages materially below said value.
29. A plate of high-resistance material having portions of the surface thereof of higher resistance than the body portion.
30. A lightning arrester comprising a plurality of plates of high resistance material disposed in contact with each other, the contacting portions of one or more of the plates having higher specific resistance than the body portions of the plates.
31. A lightning arrester comprising a plurality of plates of non-metallic material disposed in contact with each other, the contacting portions of one or more of the plates having higher specific resistance than the body portions of the plates.
32. A lightning arrester comprising a plurality of plates of high resistance material disposed in contact with each other at a relatively small number of points, the contacting portions of one or more of the plates having higher specific resistance than the body portions of the plates.
33. A lightning arrester comprising a plurality of plates of high resistance material disposed in contact with each other at a relatively small number of points and being separated at the remainder of the contact surfaces, the contacting portions of one or more of the plates having higher specific resistance than the spaced portions of the contacting surfaces.
34. A lightning arrester comprising a plurality of plates of high resistance material

4

disposed in contact with each other, the contacting portions of one or more of the plates having higher specific resistance than the body portions of the plates, the spacing and resistivity being such that the space current flow always takes the form of a glow discharge.

35. A lightning arrester comprising a plurality of plates of non-metallic material disposed in contact with each other, the contacting portions of one or more of the plates having higher specific resistance than the body portions of the plates, the spacing and resistivity being such that the space current flow always takes the form of a glow discharge.

36. A lightning arrester comprising a plurality of plates of high resistance material disposed in contact with each other at a relatively small number of points, the contacting portions of one or more of the plates having higher specific resistance than the body portions of the plates, the spacing and resistivity being such that the space current flow always takes the form of a glow discharge.

37. A lightning arrester comprising a

plurality of plates of high resistance material disposed in contact with each other at a relatively small number of points and being separated at the remainder of the contact surfaces, the contacting portions of one or more of the plates having higher specific resistance than the spacer portions of the contacting surfaces, the spacing and resistivity being such that the space current flow always takes the form of a glow discharge.

38. A space-current discharge device comprising electrode plates contacting at only a relatively small number of points, the remaining portions of the contact surfaces being spaced, the material of at least one of said plates having such resistivity as to cause the discharges in said gap to spread out in the form of a glow discharge, the contacting portions of said plate having a higher specific resistance than the spaced portions of the contacting surfaces.

In testimony whereof, I have hereunto subscribed my name this 3rd day of February 1922.

JOSEPH SLEPIAN.
